C. C. FARMER

INTERLOCK DEVICE

Filed Sept. 13, 1922

INVENTOR

CLYDE C. FARMER

BY *Wm. M. Cady*
ATTORNEY

UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

INTERLOCK DEVICE.

Application filed September 13, 1922. Serial No. 587,903.

To all whom it may concern:

Be it known that I, CLYDE C. FARMER, a citizen of the United States, residing at Pittsburgh, in the county of Allegheny and State of Pennsylvania, have invented new and useful Improvements in Interlock Devices, of which the following is a specification.

This invention relates to an interlock device adapted to be employed in connection with a switch for controlling electric train line circuits and cut-out cocks for controlling communication through fluid pressure train pipes.

Where electric train line circuits are employed on cars it is sometimes necessary to provide a manually operated switch on the cars for opening and closing the circuits independently of the electric train line couplers between the cars as, for example, in the case of cars equipped for multiple unit control and where the electric train line couplers are of the type in which the circuits are opened by the separation of the cars. In such case, when power is applied to one car power will also be applied to the other cars of the train, so that cars cannot be separated when desired, since all cars may be moved simultaneously when power is applied on one car.

The trainman may neglect to operate the switch, but if he fails to close the cut-out cock in the train brake pipe the brakes will be applied, so that the trainman may be relied on to close the cock.

One object of my invention is to provide an interlock device such that the cut-out cocks cannot be moved to the closed position unless the train line switch has been moved to its open position, so that the operator must open the switch before he can close the cut-out cock.

Another object of my invention is to provide an interlock device such that the switch cannot be moved to its closed position unless the cut-out cock is moved to its open position.

Another object of my invention is to provide an interlock device of the above character which will permit the opening and closing of the switch while the cut-out cock remains in its open position.

In the accompanying drawing; Fig. 1 is a diagrammatic view of an interlock device applied to a switch and cut-out cock con-

struction and embodying my invention and showing the switch in its open position and the cut-out cocks in the closed position, a portion being shown in section taken on the line 1-1 of Fig. 3; Fig. 2 a view of the construction shown in Fig. 1 with the switch in its closed position and the cut-out cocks in the open position; and Fig. 3 a section on the line 3-3 of Fig. 1.

In the drawing, A represents the car body to which are attached at opposite sides bracket members 1 and 2: secured to the underside of the car body is a manually operated switch device 3 containing the usual rotatable switch drum 4 having contacts for engagement with contact fingers 5 which are connected to corresponding train line circuits. For operating the drum 4 a lever 6 is secured to the drum and one end of the lever is pivotally connected to operating rods 7 and 8 which extend through the corresponding bracket members 1 and 2, the outer ends of the rods 7 and 8 being bent to form operating handles as shown.

The other end of the lever 6 is pivotally connected to a rocker arm 9 which is pivotally mounted on a sleeve 10. Slidably mounted in the sleeve 10 is a rod 11 for operating the cut-out cocks, such as the brake pipe cut-out cock 12 and the signal pipe cock 13, the respective cock levers 14 and 15 being provided with slots at their outer ends within which are pins 16 and 17 secured to the rod 11. Opposite ends of the rod 11 are pivotally connected to operating rods 18 and 19 which extend through openings in the bracket members 1 and 2.

The arm 9 carries a half round lug 20, the flat face of which is adapted to engage the upper face of the rod 11 in the position shown in Fig. 1 in which the cut-out cocks are closed, said lug being adapted to engage in a notch 21 cut in the rod 11 when the rod is in the position shown in Fig. 2, in which the cut-out cocks are open.

In operation, in the position shown in Fig. 1, the rod 11 is in the position in which the cut-out cocks 12 and 13 are held closed and the switch 3 is in its open position. It will be evident that the rods 7 and 8 cannot be operated to rotate the switch drum 4 by reason of the lug 20 engaging the upper face of the bar 11 so that the arm 9 cannot be rocked and therefore said arm acts as a lock to prevent the movement of the bar 6.

by the operating rods 7 and 8. Before the switch can be moved to its closed position, the bar 11 must be shifted to its position, as shown in Fig. 2, in which the cut-out 5 cocks are opened. In this position, one of the levers 7 or 8 may be shifted so as to rock the lever 6 and rotate the drum 4 to its closed position, since the arm 9 is now free to move by reason of the lug 20 engaging 10 in the notch 21 of the bar 11.

In the position of the parts as shown in Fig. 2, the cut-out cocks cannot be shifted to the closed position by movement of the rod 11, since the movement of the rod 11 is 15 prevented by engagement of the lug 20 in the notch 21. In order to be able to shift the cut-out cocks to the closed position, it is then necessary to first operate the switch drum by means of one of the rods 7 and 8 so 20 that the drum is turned to its open position. In this position, the lug 20 is not in engagement with the notch 21 and consequently the bar 11 may be operated to shift the cut-out cocks to the closed position.

25 It will be noted, however, that in the position shown in Fig. 2, the switch drum may be turned to its open position without operating the cut-out cocks, so that electric power may be cut off while cars are coupled 30 together to permit inspection and repairs, without causing an application of the brakes through the closing of the brake pipe cut-out cocks.

35 A locking device may be provided for locking the switch operating mechanism in either of its positions of adjustment such as a rod 22 extending through the members 1 and 2 and having the ends bent as shown to form operating handles. The rod 22 is 40 provided with a latch 23 adapted to engage notches 24 in the rod 7 in either the open or the closed position of the rod. By turning the rod 22, the latch 23 may be disengaged from the notch 24 so that the rod 7 may be 45 shifted, as desired.

50 A similar locking device may be provided for the cut-out cock operating mechanism and comprising a rod 25 carrying a latch 26 adapted to engage notches 27 in the rod 18.

Having now described my invention, what I claim as new and desire to secure by Letters Patent, is:

55 1. The combination with a switch device for controlling electric train line circuits and a cut-out cock for controlling communication through a fluid pressure train pipe, of an interlock device including an interlocking element movable with said switch 60 device and an interlocking element movable with said cut-out cock for preventing movement of the switch device in one position of the cut-out cock.

65 2. The combination with a switch device for controlling electric train line circuits

and a cut-out cock for controlling communication through a fluid pressure train pipe, of an interlock device including an interlocking element movable with said switch device and an interlocking element movable with said cut-out cock for preventing movement of the cut-out cock in one position of the switch device. 70

3. The combination with a switch device for controlling electric train line circuits and a cut-out cock for controlling communication through a fluid pressure train pipe, of an interlock device including an interlocking element movable with said switch device and an interlocking element movable with 80 said cut-out cock and adapted in one position to prevent movement of the switch device and in another position to prevent movement of the cut-out cock. 75

4. The combination with a switch device for controlling electric train line circuits and a cut-out cock for controlling communication through a fluid pressure train pipe, of an interlock device including two locking members, one movable with the switch 85 device and the other with the cut-out cock for preventing movement of the switch device in the closed position of the cut-out cock. 90

5. The combination with a switch device for controlling electric train line circuits and a cut-out cock for controlling communication through a fluid pressure train pipe, of an interlock device including two locking members, one movable with the switch 95 device and the other with the cut-out cock for preventing movement of the cut-out cock in the closed position of the switch device. 100

6. The combination with a switch device for controlling electric train line circuits and a cut-out cock for controlling communication through a fluid pressure train pipe, of an interlock device including two locking members, one movable with the switch 105 device and the other with the cut-out cock for preventing movement of the switch device from its open position with the cut-out cock 110 in its closed position.

7. The combination with a switch device for controlling electric train line circuits and a cut-out cock for controlling communication through a fluid pressure train pipe, of an interlock device including two locking members, one movable with the switch 115 device and the other with the cut-out cock for preventing movement of the cut-out cock from its open position with the switch device in its closed position. 120

8. The combination with a switch device for controlling electric train line circuits and a cut-out cock for controlling communication through a fluid pressure train pipe, of an interlock device including two locking members, one movable with the switch 125 device and the other with the cut-out cock for 130

5 preventing movement of the switch device from its open position with the cut-out cock in its closed position and for preventing movement of the cut-out cock from its open 5 position with the switch device in its closed position.

10 9. The combination with a switch device for controlling electric train line circuits and a cut-out cock for controlling communication through a fluid pressure train pipe, of manually operated means for operating said switch device, separate manually operated means for operating said cut-out cock, and an interlock device for preventing movement of one operating means when the other operating means is in a predetermined 15 position.

20 10. The combination with a switch device for controlling electric train line circuits and a cut-out cock for controlling communication through a fluid pressure train pipe, of manually operated means for operating said switch device, separate manually operated means for operating said cut-out cock, and an interlock device for locking the cut-out cock operating means against movement in the switch closing position of the switch 25 operating means and the cut-out cock open position of the cut-out cock operating means.

30 11. The combination with a switch device

for controlling electric train line circuits and a cut-out cock for controlling communication through a fluid pressure train pipe, of manually operated means for operating said switch device, separate manually operated means for operating said cut-out cock, and an interlock device adapted to be locked against movement by the cut-out cock operating means in its cock closed position for preventing movement of the switch operating means from its open position.

12. The combination with a switch device for controlling electric train line circuits, manually operated means for operating said switch device, a cut-out cock for controlling communication through a fluid pressure train pipe, and manually operated means for operating said cut-out cock, of an interlock device comprising a pivoted arm operatively connected to said switch operating means, a locking member carried by said arm and adapted to engage said cut-out cock operating means in one position to prevent movement of the locking member and to engage said cock operating means in another position so as to prevent movement of the cock operating means.

In testimony whereof I have hereunto set my hand.

CLYDE C. FARMER.
